The ornamental design of a supply pod dispenser, as shown and described.

DESCRIPTION

FIG. 1 is a front perspective view of the supply pod dispenser showing my new design;

FIG. 2 is a front view of the supply pod dispenser thereof;

FIG. 3 is a back view of the supply pod dispenser thereof;

FIG. 4 is a left side view of the supply pod dispenser thereof;

FIG. 5 is a right side view of the supply pod dispenser thereof;

FIG. 6 is a top view of the supply pod dispenser thereof; and,

FIG. 7 is a bottom view of the supply pod dispenser thereof. The broken lines shown throughout the views of the supply pod dispenser, which are immediately adjacent to claimed surfaces, represent the bounds of the claimed design, while all other broken lines are directed to the environment and are for illustrative purposes only, and form no part of the claimed design.
